UNITED STATES PATENT OFFICE.

JOHN BEAMISH HAMILTON, OF TENBY, ENGLAND.

DRAIN OR SEWER PIPE JOINT.

SPECIFICATION forming part of Letters Patent No. 634,136, dated October 3, 1899.

Application filed March 22, 1899. Serial No. 710,113. (No model.)

To all whom it may concern:

Be it known that I, JOHN BEAMISH HAMILTON, a subject of the Queen of England, residing at Tenby, England, have invented certain new and useful Improvements in or Relating to Drain and Sewer Pipe Joints, (for which I have made application in Great Britain, No. 24,722, dated November 23, 1898,) of which the following is a specification.

10 This invention relates to drain and sewer pipe joints; and its object is to enable such joints to be effectively cemented, particularly in that part which lies underneath and out of sight of the workman.

15 According to this invention I form a trough-shaped mold or casing of suitable material, preferably the same as that of which the pipes are formed. This trough is of convenient shape externally, but internally semicircular, being curved and shaped to fit the joint.

20 In use the trough is placed beneath the joint and either filled with cement before the pipes are laid or cement is poured into the trough after the pipes have been placed in position.

25 By this means the under side of the joint is properly cemented the whole way around and a tight joint is obtained. The interior of the end of each trough is preferably so shaped that it fits closely about the pipes on either side of

30 the joint, thus preventing the cement at the bottom from being displaced by pressure from above. There is also a provision by means of stops, against which the faucet of the contained pipe impinges, which prevents any

35 possible disturbance of or pressure on the cement in the trough. The shape of the trough may be varied in many respects to suit requirements. The troughs may, if desired, be applied to existing faulty joints

40 without disturbing the pipes.

In the accompanying drawings, Figure 1 is a perspective view of a trough. Fig. 2 is a similar view of a modified form. Fig. 3 is a central longitudinal section of Fig. 1, showing the manner in which a joint is made.

45 Fig. 4 is a sectional plan, and Fig. 5 is a transverse section on the line 5 5 of Fig. 3.

A trough-shaped mold or casing A, of any suitable shape externally, such as circular, 50 rectangular, or polygonal, is made of earth-

enware, concrete, or the like. Internally the trough is semicircular and is shaped to fit the joint, the diameter of the end A' corresponding to the outside diameter of the pipes to be jointed. Within the end A' and adjacent to it the diameter is increased at A² to correspond to the internal diameter of the faucet of a pipe, and beyond this again at A³ the diameter corresponds to the external diameter of the faucet. Thus the parts A' and A² form two internal contiguous collars in the trough. To prevent mistakes in jointing, the trough is preferably made symmetrical, although it is obvious that the part A² may be dispensed with at one end. 55

In making a joint a layer of cement or other binding material is placed within the trough on the parts A² and A³ and the faucet B of a pipe C upon the cement, the pipe itself resting on the part A', thereby preventing the cement beneath from being displaced by pressure from above. Binding material is now placed within the faucet B and the spigot D of the other pipe inserted into the faucet B, resting on the other end A' of the trough, the joint being then finished on the upper side in the usual way. The pipes may, however, first be placed in position on the trough and the binding material poured between them. 70

In order to prevent any possible disturbance of or pressure on the binding material in the trough, stops A⁴ are formed on the sides of the part A² at the junctions of A² and A³, the faucet B bearing against these stops. 75

If desired, the space E may also be filled with the binding material in order to further prevent displacement of the parts forming the joint. 80

The interior of the trough may be a smaller arc than a semicircle, although the latter is 90 the more convenient.

The trough may vary in shape and details to suit various requirements and is especially adapted for jointing pipes that are so laid that a workman can only get at one side. 95

If desired, two or more troughs may be used, so as to completely encircle the joint.

I claim—

1. The herein-described device for use in forming pipe-joints consisting of the mold or 100

easing for holding the cement and provided with the stops against which the faucet of the contained pipe abuts; as and for the purpose set forth.

5 2. The herein-described device for use in forming pipe-joints consisting of the mold or easing formed with end supports upon which the ends of the pipes rest and also provided with stops against which the faucet of the

contained pipe abuts; as and for the purpose set forth.

In testimony whereof I hereto set my hand in the presence of the two subscribing witnesses.

JOHN BEAMISH HAMILTON.
